UNITED STATES PATENT OFFICE.

EDWIN R. RAND, OF NEWTON, ASSIGNOR TO THE BOSTON CAR SPRING COMPANY, OF BOSTON, MASSACHUSETTS.

ACID-PROOF RECEPTACLE AND LINING THEREFOR.

SPECIFICATION forming part of Letters Patent No. 394,296, dated December 11, 1888.

Application filed April 19, 1887. Serial No. 235,324. (No model.)

To all whom it may concern:

Be it known that I, EDWIN R. RAND, of Newton, county of Middlesex, State of Massachusetts, have invented an Improvement in 5 Acid-Proof Receptacles and Linings therefor, of which the following description, in connection with the accompanying drawings, is a specification, like letters on the drawings representing like parts.

10 My invention relates to a receptacle capable of resisting the action of acid liquids, being especially intended to constitute the outer or main receptacle of a galvanic battery.

In another application I have shown and 15 described an acid-proof receptacle composed of a metal box having a cover of gutta-percha or rubber vulcanized upon it.

For some reasons it is desirable to have the lining removable; and the present invention 20 consists partly in a lining or covering for a rigid case or frame, said lining being composed of vulcanized rubber made into a bag or receptacle having its exterior size and shape correspond with the interior size and shape 25 of the rigid receptacle, and having around its upper edge a downwardly-turned lip or flange, which extends down the outer surface of the rigid case, and thus supports the lining and keeps its upper part distended and prevents 30 possibility of the liquid finding its way between the rigid case or frame and lining. This combination of rigid case and flexible lining has many advantages, which will be readily apparent. For example, a case might 35 be broken, so that it alone could not hold the liquid, although it would still afford a sufficient support for the lining, so that the entire receptacle would be nearly if not quite as effective as before and would answer until a 40 new case could be provided; or if a lining should become broken or torn another could be quickly substituted; and if the batteries were used, for example, on railway-trains a few extra linings could be easily carried, as 45 they would fold up and occupy but little space, and might in many cases prevent the entire battery from being disabled. The case or rigid frame-work that supports the rubber lining may be of any desired material, preferably of papier-maché or some of the other well-known forms of molded pulp; or they may

be of wood, and will preferably be treated to render them to a certain extent acid-resisting, so that a short exposure to the action of acids would not injure or destroy them. The box 55 or case when lined with soft rubber may be made much thinner and lighter than it safely could without such lining, and the lining would be of advantage even with the usual acid-proof glass or hard-rubber receptacles, as 60 a breakage which did not wholly destroy the receptacle would probably leave a sufficient portion of it to sustain the lining until the new case could be provided, while without such lining the slightest breakage or crack in 65 the case would permit the liquid to escape, and thus not only disable the battery, but expose the surrounding objects to the injurious effects of the acid.

Figure 1 is a sectional view of a lining or 70 covering for a receptacle to hold acids embodying this invention, and Fig. 2 a corresponding sectional view of the rigid case or frame for said receptacle.

The case or frame *a*, Fig. 2, may be of any 75 suitable or usual size, shape, and construction, being shown as provided with internal ledges or cleats, *a'*, to support the inner members of the battery. While the invention is not limited to any specific construction or material for the main case *a*, it is believed that paper or wood pulp formed or molded and compressed by the well-known processes and treated to render it impervious to liquids, and preferably to a greater or less extent acid- 80 resisting, is the best for this purpose. In order to protect the said case from continuous action of the acid liquids to be contained within it, and to prevent leakage of such liquids if the said case should be partially 85 broken or cracked, it is, in accordance with this invention, provided with a lining or covering, *b*, composed of rubber molded and vulcanized in proper shape to fit the interior of the said case *a*, being shown in this instance 90 as having recesses *b'* to receive the cleats or ledges *a'* at the bottom of the case.

In order to keep the lining *b* at all times extended, and to prevent possibility of any of the liquid entering between the said case and 100 its covering, the upper portion of the latter is molded with an outwardly and downwardly

turned flange, b^2 , which fits over the upper edge of the receptacle a and extends a greater or less distance down the outer surface thereof, as may be desired.

5 The bag or covering b may be folded into small space when not in use, and a new covering can be readily applied to a case when an old one has become damaged.

The covering b is sufficient in itself to contain the acid liquid, and the function of the case a is merely to keep the said covering b in the proper shape or position, which can readily be done by a skeleton case or frame, or by a case or frame such as shown, if it 15 were cracked or had a hole knocked in the side or bottom of it, which would, without the lining, render it absolutely worthless and for the time being disable the battery of which it formed a part.

20 By having the case itself liquid-tight and to a greater or less degree acid-resisting the liability to accidents is greatly diminished, as the lining may be depended upon to hold the liquid when the case is damaged, as before stated; or the case may retain the liquid 25

temporarily if the lining should become torn or broken, thus keeping the battery intact until an opportunity is afforded for supplying a new lining.

I claim—

30 1. A receptacle composed of a rigid case or frame and a flexible removable internal covering or lining therefor composed of soft or elastic vulcanized rubber, substantially as described.

35 2. The combination of a rigid case composed of papier-maché with a covering composed of vulcanized rubber molded to fit the interior of the said case, and provided with an outwardly and downwardly turned flange to 40 fit the upper edge and a portion of the exterior of the said case adjacent thereto, substantially as described.

45 In testimony whereof I have signed my name to this specification in the presence of two subscribing witnesses.

EDWIN R. RAND.
